(57) **CLAIM**

The ornamental design for a canopy for a machine, as shown and described.

DESCRIPTION

FIG. 1 is a front isometric view of a canopy for a machine, showing our new design;

FIG. 2 is a front view thereof;

FIG. 3 is a rear view thereof;

FIG. 4 is a left side view thereof, wherein the right side view is a mirror image thereof;

FIG. 5 is a top view thereof; and,

FIG. 6 is a bottom view thereof.

The phantom dashed lines of FIGS. 1–6 showing the hardware and the handle are for illustrative purposes only and form no part of the claimed design relative to the particular embodiment shown.

The broken line showing in FIGS. 1–6 of the hardware and the handles is included for the purpose of illustrating environmental structure and forms no part of the claimed design.
